VALVE FOR COOKING UTENSIL LID

Frank E. Stepanek, Lagrange Park, Ill., assignor to American Home Products Corporation, New York, N.Y.

Filed Dec. 13, 1971, Ser. No. 207,720

Term of patent 14 years

Int. Cl. D7—02

U.S. Cl. D7—129

FIG. 1

FIG. 4

FIG. 5

FIG. 2

FIG. 3

FIG. 1 is a top perspective view of a valve for a cooking utensil lid showing my new design.

FIG. 2 is an elevational view thereof taken in a direction showing the full-height vertical slot which is identical to a vertical slot located 180° around the circumference of the valve.

FIG. 3 is an elevational view thereof taken 90° in either direction from the elevational view of FIG. 2.

FIG. 4 is a horizontal section taken along line 4—4 of FIG. 3.

FIG. 5 is a bottom plan view thereof.

I claim:

The ornamental design for a valve for cooking utensil lid, as shown.
